UNITED STATES PATENT OFFICE.

MARTIN L. WILLIAMS, OF SOUTH BEND, INDIANA, ASSIGNOR, BY MESNE ASSIGNMENTS,
TO AMERICAN SLEEVE-VALVE MOTOR COMPANY, A CORPORATION OF DELAWARE.

LUBRICATING SYSTEM.

1,303,622.

Specification of Letters Patent.

Patented May 13, 1919.

Application filed June 9, 1915, Serial No. 33,017. Renewed October 2, 1918. Serial No. 256,629.

To all whom it may concern:

Be it known that I, MARTIN L. WILLIAMS, a citizen of the United States, residing in South Bend, in the county of St. Joseph and State of Indiana, have invented certain new and useful Improvements in Lubricating Systems, of which the following is a specification.

This invention relates to improvements in lubricating systems and more particularly to improvements in lubricating systems for engines, such as gas, steam or vapor engines, though in its broader aspects the invention is not limited to use with any particular type or types of engines.

Among the salient objects of the invention are to provide a lubricating system which can be successfully employed with engines having a port or ports controlled by a rotating member; to provide a lubricating system which can be successfully employed with engines having their ports controlled by movable sleeves, either reciprocating or rotating; to provide a construction in which the amount of lubrication fed to the contacting surfaces is automatically controlled by the speed of the engine; to provide a construction in which the ports through which the lubrication is admitted are controlled by a valve preferably spring pressed to its seat, and opened in timed relation to the speed of the crank shaft; to provide a construction in which valve or other member controlling the ports is positively opened by a cam, or other member carried by a part normally movable in the operation of the engine, such as the sleeve which controls the engine ports; to provide a construction in which the lubricant can be maintained under pressure, and the pressure automatically increased with the increase of the speed of the engine; to provide a construction in which the lubricant is positively fed (as by a pump) to all of the working parts and any surplus oil properly filtered and returned to the lubricant chamber in the crank case; to provide a construction in which the lubricant chamber in the crank case is divided longitudinally into a plurality of compartments, the oil being free to pass from the forward compartment to the rear compartment in which the pump is located, but not to return from the rear compartment to the front com-

partment, thus insuring a supply of lubricant to the pump at all times; to provide a construction in which the leakage of either the lubricant or gas past the space between the ends of the split ring is prevented without excessive friction between the movable parts; to provide a construction in which the lubricant is fed from one bearing to another through the hollow crank shaft without any of the lubricant being compelled to travel against the centrifugal force produced by the revolving arms of the crank shaft; to provide a construction in which an oil chamber is provided at the top of the port controlling sleeve and the lubricant is fed from this chamber over the top of the sleeve and also downwardly through a conduit bored lengthwise in the sleeve thus permitting the proper quantity of lubricant to be furnished to the portion of the sleeve below the ports; to provide a construction in which a thin film of lubricant extends completely over the surface of the moving parts, and the supply of lubricant stopped when the engine feed is shut off; and in general to provide a construction which is free from complicated parts, is positive in action, and will feed the proper quantity of lubricant to the moving parts of a rotary sleeve or other types of engine.

In engines of the sleeve type, particularly those used as internal combustion engines, it is necessary to provide a sufficiently tight seal between the sleeve and the member in which it moves to prevent the escape of the gases which are under high pressure. This fact, taken together with the relatively large area of contacting surfaces make it imperative in engines of this type that a thin film of oil be fed upon and constantly cover the contacting surfaces of the valve sleeve and its seat. The present invention contemplates a construction in which the oil is not only positively fed to the contacting surfaces but is evenly distributed over the entire area and is fed to the valve and the various bearings in proportion to the speed of the engine so that the amount of lubricant shall not be excessive.

In the drawings:

Figure 1 is a side elevation, various parts being shown in section, of an engine embodying my invention.

Fig. 2 is an enlarged irregular cross section through one of the parts taken at right angles to the view shown in Fig. 1.

Fig. 3 is a plan view looking down on the 5 crank shaft.

Fig. 4 is an enlarged fragmentary cross section through one of the cylinders.

Fig. 5 is a fragmentary horizontal section taken on the line 5—5 of Fig. 4.

10 Fig. 6 is a fragmentary vertical section taken on the line 6—6 of Fig. 5.

Fig. 7 is a fragmentary horizontal section through one of the sealing rings.

15 Fig. 8 is a fragmentary side elevation showing the manner of sealing across the ends of the split ring.

Fig. 9 is an enlarged vertical section through the lower part of the engine in the plane of the center bearing.

20 Fig. 10 is a horizontal section looking down on the line 10—10 of Fig. 4.

Fig. 11 is a fragmentary vertical section on the line 11—11 of Fig. 1.

25 Referring to the drawings and describing first the general construction of the engine, 1 designates a multi-cylinder engine having a plurality of cylinders 2 surrounded by water cooling spaces 3 in the usual manner. Each of the cylinders are provided with an 30 inlet port 4 and an exhaust port 5, and in the particular type of engine shown, the passage of gases into the cylinder through the inlet port and the exhaust gases out of the cylinder through the outlet port is controlled 35 by a rotary sleeve 6 mounted within a removable lining or bushing 7. At its lower end this rotary sleeve is provided with a worm gear 8 meshing with a worm wheel 9 mounted upon a shaft 10 which is driven in 40 timed relation to the crank shaft 11 by means of intermeshing gears 12 and 13. Reciprocating within the rotary sleeve 6 is a piston 14 connected to the crank shaft 11 by means of a connecting rod 15 in the usual 45 manner.

The upper end of the cylinders is provided with a slab head 16, which is protected from the direct heat of the expansion chamber 17 by means of a cap 18. Depending from the 50 latter and extending within the upper end of the rotating sleeve is a split ring 19, the construction being such that the ported portion of the rotating sleeve extends intermediate the split ring 19 and the liner or bushing 7. The split ring 19 has on its upper edge a recess portion 20 registering with a corresponding portion 21 in the cap 18.

It will be noticed that the upper wall of the recessed portion 20 is beveled, and positioned into the recess so as to also extend into the recess 21 is a spring-supporting ring 22. The construction is such that while the split ring 19 is supported from the cap 18 so that it can have a slight movement relative to the cap to compensate for any inac-

curacies in alignment, a gas-tight joint is always maintained between the ring and the cap because of the spring-supporting ring pressing against the upper cammed edge of the ring 19.

70 Describing now in detail the lubricating system, it will be noticed that at the lower end of the crank case is a lubricant chamber 23 connected to a second lubricant chamber 24 and divided from the latter by a partition wall 25, the two chambers connecting through a port 26 controlled by a trap or check valve 27. This check valve is so arranged that the lubricant can flow from the chamber 24 into the chamber 23, but cannot 80 flow back from the latter into the former. The purpose of this check valve 27 is to prevent the lubricant from flowing back out of the chamber 23, in which the pump 28 is located.

85 The lubricant contained in the chambers 23 and 24 is drawn out of the former through an inlet 29 connected to the suction pump 28 from which it is forced through the outlet 30 to the various bearings and other members to be lubricated. Any surplus oil is drawn back into the chamber 24 by means of a return pipe 31, which discharges through a screen 32 into the chamber 24. Near 90 its forward end, the chamber 24 is provided with a downwardly offset portion 33, the top of which is substantially in line with the valve 27 and the bottom of the chamber 24, so that when there is any substantial amount of lubricant in the latter, it will lift 100 the valve 27 and pass into the chamber 23. Thus the oil, by means of the force pump 28 is continuously circulated to the various parts to be lubricated.

95 As shown in Figs. 2 and 3, the pump is 105 driven in timed relation to the engine speed by means of a gear wheel 34 meshing with a gear wheel 35, mounted on a vertical shaft 36. This shaft near its upper end is provided with a worm gear 37, which meshes 110 with one of the worm wheels 9 so that the amount of lubricant pumped is proportioned to the speed of the engine.

115 Referring now in detail to the means for conducting the oil to the various bearings, port controlling sleeves, etc., the pipe 30 has a branch 45 extending into the crank-case, and terminating in an L-coupling 38, from opposite ends of which lead pipes 39 and 40 extending to the crank shaft bearings 41 and 120 42. The pipe 40 is also provided with a branch pipe 43 extending to the center bearing 44. At its upper end the conduit 30 is connected with a horizontally extending conduit 46 which furnishes lubricant to the upper oil deck as hereinabove described in detail, and with a second vertically extending conduit 47. The latter is provided at its upper end with a T-elbow 48, to one end of which is connected an indicator 49, and in the oppo- 125 130

site end of which is connected a conduit 50 having a plurality of connections 51, for conducting the oil from the pipe 50 to the various individual cylinders.

- 5 To the connection 51 is secured a pipe 52 which leads downwardly through the head and terminates in a recess 53 formed in the cap 18. The pipe 52 has a transversely extending bore 54 which registers with a corresponding bore 55 formed in the cap. The outer end of the bore 55 is closed by a ported plug 56, the port of which is controlled by a valve member 57, having at its outer end a projecting lug 58, and at its inner end a stem 59. Sleeved upon the stem 59 is a spring 60 which serves to normally hold the valve 57 to its seat with the lug 58 projecting beyond the end of the plug 56, and into the chamber 61 formed at the upper end of the sleeve 6.
- 20 The construction above described is such that the spring 60 normally holds the valve 57 to its seat and prevents the flow of oil into the chamber 61, and the following means are provided for moving the valve away from its seat so as to permit the passage of lubricant from the pipe into the chamber 61. As shown in detail in Figs. 5 and 6, the upper end of the sleeve 6 is provided with a pin 62 which extends upwardly flush with the top of the sleeve 6 and is so positioned that approximately one-half of it extends into the plane of the chamber 61. Thus as the sleeve rotates to open and close the ports, the curved surface of the pin 62 will strike against the end of the lug 58 and acting as a cam will force the lug backward, thus moving the valve 57 from its seat and admitting the lubricant which is under pressure into the chamber 61. It is obvious that by sup-
- 35 plying a plurality of pins 62, the amount of lubricant fed in each revolution of the sleeve could be changed, but whether one pin or more are used, the amount of lubricant fed into the chamber 61 will be in direct proportion to the speed of the engine, since the valve is spring-pressed to its seat, and, for each pin employed, will be opened as many times as there are revolutions of the sleeve and each time opened will remain open the
- 40 length of time necessary for the spring to return to its seat.

In order to prevent the lubricant leaking out of the chamber 61, down through the opening between the ends of the split ring, 55 I preferably employ the following arrangement: Near the upper end of the ring 19 is a sealing member 63, while near its lower end is a similar sealing member 64. As shown in detail in Fig. 7, the split ring 19 near its ends 65 and 66 is provided with recess portions 67 and 68 within which the sealing members 63 and 64 are adapted to seat. Both of these sealing members extend across the opening formed between the adjacent 60 ends of the split ring, the member 63 being

secured to the ring by a pin or other securing member 69 and the member 64 secured by a similar pin 70.

The upper sealing member 64 prevents the passage of the lubricant from the chamber 61 into the cylinders by bridging the opening between the ends 65 and 66 of the split ring 19. The lower sealing member 65 is preferably positioned in the horizontal plane of a port 71 which opens toward the sealing ring 19 and is connected with the chamber 61 by means of a bore 72 extending down through the wall of the sleeve 6. The purpose of the port 71 and bore 72 is to feed oil from the chamber 61 to that portion of the outer surface of the split ring 19 which is below the inlet and exhaust ports. While ports similar to 71 might be employed leading to the inner surface of the bushing 7, in the present construction a sufficient amount of oil is fed over the top of the sleeve and down around the outside thereof, and down between the sleeve and the split ring 19 to maintain a thin film of oil over the entire surface. Any surplus oil fed down between the sleeve and the bushing is drawn back into the upper oil deck 73, although in some cases it may be advisable to provide the sleeve with a plurality of small ports 74 through which the oil can pass to the interior surface of the sleeve and thus aid in lubricating the contacting surfaces of the sleeve and piston.

However, for lubricating the pistons, I preferably utilize the surplus oil from the connecting rod bearings, the lubricant being supplied to these bearings in the following manner: Lubricant is supplied to the piston rod bearings 75 and 76 from the center main crank shaft bearing 44 and to the connecting rod bearings 77 and 78 from the end main crank shaft bearings 41 and 42. As shown in Fig. 1, the bearing portions of the crank shaft are provided with a central bore 79, the ends of which are closed by plugs 80 and 81. The chambers thus formed are connected by bores extending through the crank arms. However, the connection between the bearings 77 and 83 and between the bearings 78 and 84 if connected by bores 110 through the crank arm would compel the lubricant to travel toward that portion of the crank shaft from which it is thrown by centrifugal force. I, therefore, employ a pair of by-pass conduits 87 and 88 for connecting the respective bearings, these conduits being curved as shown in Fig. 2 so that the lubricant is permitted to travel from one bearing to the other in the arc of a circle drawn from the center of the crank 115 shaft. This construction permits the lubricant to be fed from one connecting rod bearing to another through an intermediate bearing without having to travel back nearer the center of the shaft, or to overcome the 120 125 130

centrifugal force which throws the lubricant out away from the center.

The various hollow chambers 79 contained within the connecting rod bearings are provided with ports 89, which connect with a longitudinal bore 90 extending through the connecting rod 15 so as to furnish oil to the piston pin bearing 91. There is sufficient excess of oil furnished to the connecting rod bearings so that the surplus is thrown up against the inner wall of the sleeve 6, through the tube 89', and lubricates the contacting surfaces of the sleeve and piston. by making the tube 89' of a predetermined size, the amount of lubrication thrown against the sleeve 6 can be regulated. Moreover, the amount of lubricant fed through the tube 89' is proportioned to the speed of the engine, since for each revolution of the crank shaft, the port 89 registers with the inner end of the tube 89'. If desired a baffle plate such as indicated at 92 may be employed for preventing too much lubricant being thrown against the wall of the sleeve.

In addition to the surplus which is drawn back into the upper deck 73, the latter is supplied with lubricant from the conduit 46 by a valve 94, which is actuated by a rock arm 95, having a connection to the carbureter throttle valve (not shown) by means of a rod 96, the construction being such that when the throttle valve is adjusted to supply more fuel to the engine, the arm 95 is actuated by movement of the rod 96 so as to restrict communication between the conduit 46 and the port 93, thus forcing more of the lubricant to pass through the openings to the various bearings and sleeves. Extending through the oil deck 73 is the worm wheel shaft 10, this shaft being mounted in end bearings 97 and 98, and a center bearing 99, and surrounding the bearings 97, 98 and 99 are oil pockets 100, 101, and 102 respectively.

The lubricant discharged from the port 93 enters the pocket 101 from which it flows into the worm wheel chamber 103, through the port 104. From the chamber 103 the lubricant passes into the pocket 102 through a port 105 and through a similar port 106 is fed into the worm wheel chamber 107. When the supply of lubricant in the last mentioned chamber reaches the level of the port 108, part of it will pass into the pocket 100. From this pocket lubricant is supplied to the bearing 97 through a port 109 and through a similar port 110, lubricant is fed from the pocket 101 to the bearing 98. The lubricant for the center bearing 99 is fed through a groove 111, opening at its opposite ends into the chamber 103 and 107. It will be noticed that the location of the ports connecting the oil pockets and chambers is such that a constant level of lubricant is maintained in the upper deck and thus the

worm wheels which drive the rotary sleeves, run in a bath of oil. Any surplus lubricant is drawn back through the return pipe 31 and filter 32 into the chamber 24.

From the above description it will be apparent that the entire lubricating system is so arranged that the lubricant is positively fed to the contacting surfaces of all the moving parts even when the engine is inclined forwardly or rearwardly. Also the amount of lubricant supplied to the rotary sleeves is directly proportioned to the amount required and this is of material importance since excessive lubrication in this type of engine is objectionable as well as insufficient lubrication. The entire construction is free from complicated parts and in case of repair or replacement of any part, the lubricating system does not interfere with the accessibility of the various other engine parts. Moreover, the construction is one of extreme simplicity and an engine embodying my lubricating system can be economically manufactured and conveniently assembled. While I have shown and described a particular embodiment of my invention, it is obvious that various changes in construction and combination of parts can be made, and I do not, therefore, desire to limit the invention except as specified in the appended claims.

I claim as my invention:

1. In a lubricating system, the combination with a ported cylinder and a movable sleeve controlling the ports of said cylinder, of means for feeding lubricant to the contacting surfaces of the movable sleeve and cylinder, and a member carried by said sleeve for governing the amount of lubricant fed.

2. In a lubricating system, the combination with a ported cylinder and a movable sleeve controlling the ports of said cylinder, of means for feeding lubricant to the contacting surfaces of said sleeve and cylinder comprising a lubricant chamber, a valve controlling the flow of lubricant to said chamber, and a member carried by the movable sleeve controlling said valve.

3. In a lubricating system, the combination with a ported cylinder and a movable sleeve controlling the ports of said cylinder, of means for feeding lubricant to the contacting surfaces of said sleeve and cylinder comprising a lubricant chamber at the top of the sleeve, a passageway for supplying lubricant to said chamber, a valve controlling said passageway, a pin carried by said valve, a spring for pressing said valve to its seat to close communication through said passageway and a cam member driven in timed relation to the speed of the engine for engaging said pin and forcing the valve from its seat against the tension of said spring.

4. In a lubricating system, the combination with a pan into which the surplus lubricant drains, a transverse wall dividing said pan into two substantially similar compartments, one of which receives said surplus lubricant, a pump located in the other compartment, and a trap valve for permitting the lubricant to flow from the first named compartment into the other, but preventing reverse flow of the lubricant.
5. In a lubricating system, the combination with a pan into which the lubricant drains, of a transverse partition wall dividing said pan into two compartments, a lubricant pump in one compartment, a return pipe for discharging the lubricant into the other of said compartments, and a trap valve for permitting the lubricant to flow from the last mentioned compartment into the first mentioned compartment, but preventing reverse flow of the lubricant.
6. In a lubricating system, the combination with spaced crank shaft bearings, of a crank shaft mounted in said bearings, said crank shaft having a plurality of connecting rod bearings offset from the axis of the crank shaft bearing, and means for conducting lubricant from one of the offset connecting rod bearings to another bearing in the arc of a circle having its center coincident with that of the main crank shaft.
7. In a lubricating system, the combination with spaced crank shaft bearings, of a crank shaft mounted in said bearings, said crank shaft having a plurality of connecting rod bearings offset from the axis of the crank shaft bearings, and means for conducting the lubricant from one of the offset connecting rod bearings to another bearing, comprising a by-pass conduit so constructed that the lubricant in passing from one connecting rod bearing to the other, does not have to travel back toward the axis of the crank shaft bearing.
8. In a lubricating system, the combination with an oil deck, of a gear shaft extending through said oil deck, bearings for said shaft in said deck, and lubricant pockets formed adjacent said bearings so as to maintain a supply of lubricant adjacent said bearings when the oil deck is inclined.

MARTIN L. WILLIAMS.
